STOWING FACILITY FOR COMMODITIES IN
RAILWAY AND OTHER VEHICLES, AND IN
STORAGE WAREHOUSES

Edward A. Sweeley, Alexandria, Va., and Norman T. Anderson, Washington, D. C., assignors to Fruit Growers Express Company, a corporation of Delaware

Application June 3, 1935, Serial No. 24,754

31 Claims. (Cl. 105—372)

This invention relates to an arrangement of elements for supporting fragile, perishable, or other commodities while in storage, or for transportation in railway cars, ships, trucks or the like; and more particularly it has application to a railway car construction designed to facilitate storage of the cargo therein, so that the loading space of the car may be more efficiently utilized. In its broader aspect, however, the invention is equally applicable to cars, trucks, ships and storage houses, generally, where it is desirable to divide the load to be stored in order to minimize damage to the goods by crushing, and to obtain improved ventilation, refrigeration, or aeration of the commodities during their transportation or storage.

As is generally known, shipments for transportation in refrigerator cars and other vehicles may be in bulk, bags, sacks, boxes, crates, cans, barrels, and the like; and where the shipment is in sturdy containers, such as, crates or barrels, the latter may be stacked one upon another to occupy substantially the entire storage space, without incurring risk of appreciably damaging the shipment. In this case, only one deck or floor is necessary to support the load.

Where, however, the goods are in bulk, or in flexible containers, the perishable characteristics of the goods, and their susceptibility to damage by bruising must be taken into consideration when loading or storing. As an example of goods in such container, oranges and other citrus fruits are stored or shipped in special sacks or cartons. According to the usual shipping or storing method of today, the goods are merely piled on the floor in bulk, sacks, bags or cartons. In order to meet the present minimum loading of railway and other vehicles, as required by the carriers, shipments are necessarily piled to such extent that the weight upon the fruit near and at the bottom of the pile, frequently causes those goods to be mashed, bruised or otherwise damaged. With such loading method, a shipment of oranges, watermelons, potatoes, cabbages or other similar commodity, often reaches its destination with some loss or damage to goods, resulting principally from the loading method employed. To obviate this disadvantage, the present invention provides auxiliary load decks, positioned intermediate the ceiling and floor of the shipping or storage space, and thus divide the goods into parts, so that the weight on the goods on each deck is materially reduced and maintained within safe limits. The possibility of frail commodi-

ties being damaged in storage or during transit is thereby substantially eliminated.

It is, therefore, an object of this invention to provide a construction for a railway or other vehicle, such as a refrigerator car, or for a storage warehouse, so that its loading space is readily convertible for either single or multiple deck loading in accordance with the character of the goods to be shipped or stored.

Another object is to provide equipment for stowing fruits, vegetables, and the like, in a vehicle or warehouse, so as to secure a maximum loading with the minimum bruising, and this without diminishing the loading or stowing space for other uses.

A further object of the invention is to provide stationary or mobile storage facility with folding deck equipment, such that a loading deck, when not in use may be easily stored in an out-of-the-way position against a side wall, to afford unrestricted loading space for single deck loading which conforms in dimensions to standard specifications, especially for cars and trucks.

It is another object of this invention to have a deck rack received along the wall of a storage room, refrigerator car, or other vehicle so that substantially the entire side-wall surface of the loading space will be flush, and free from parts which project into or offer any obstruction to the loading space.

The invention also has among its objects to provide a compact rack structure that can be used for double-deck loading purposes, or folded into an out-of-the-way position on the side-walls so that the wall and rack will present a substantially flush surface for single deck loading of commodities that may be packed in crates, boxes, baskets, drums or other type of container, in which event, it is not necessary to guard against bruising or the like.

It is still another object of the invention when used on refrigerator cars, trucks, ships, or warehouses, to provide for adequate air circulation between the refrigerant containing compartments and the loading space, when such space is converted for double decked loading.

It is a further object of the invention to provide means for dividing the load to be stored, so as to obtain better ventilation, refrigeration, and aeration, for a perishable loading.

It is another object to provide an improved structure for deck racks.

Another object is to provide improved supporting means for a deck rack.

Still another object is to provide improved

means for supporting a deck rack in either a vertical or horizontal position.

A further object is to provide an improved gate and gate supporting means, which is especially useful in railway cars, trucks, or other vehicles.

A still further object is to provide a gate structure suitable for use with double deck rack equipment.

10 Other objects and advantages will be apparent from the following detailed description of a preferred embodiment of the invention.

In the accompanying drawings, Figure 1 is a cross sectional view, in elevation, of one end of a refrigerator car equipped with an embodiment of this invention.

Figure 2 is a cross sectional view, in perspective, taken on the line 2—2 of Figure 1.

For purposes of illustration, Figure 1 shows one 20 deck rack in its raised position, and three deck racks lowered; while Figure 2 shows the racks at the left raised, and the racks on the right lowered.

Figure 3 is a front elevational view, on an enlarged scale, of the ventilation opening in a bulk-head, and its shutter or closure, shown in position in Figures 1 and 2.

Figure 4 is a cross sectional view taken on line 4—4 of Figure 3, with the shutter in the closed position.

Figure 5 is a perspective view on an enlarged scale of one of the rack latches and its support shown in Figures 1 and 2, the rectangular shank of the stud or bolt for supporting the latch being shown in cross-section.

Figure 6 is a top plan view of one of the deck racks shown in Figures 1 and 2.

Figure 7 is a bottom plan view of the deck rack shown in Figure 6, and also an enlarged front 40 elevation of the raised deck rack shown in Figure 1, the deck rack being mounted on the horizontal flange of an angle iron rail.

Figure 8 is a cross sectional view taken on line 8—8 of Figure 6.

45 Figure 9 is a view partly in cross section and on an enlarged scale of a detail of Figure 7.

Figure 10 is a perspective view, partly in cross section and partly broken away, showing specific details of the hinge support for deck racks.

50 Figure 11 is a front elevational view, on an enlarged scale, of one of the deck gates of Figure 1, suspended in vertical position by its supporting hooks.

Figure 12 is a view, partly in cross section, on 55 an enlarged scale of the gate, its supports, and gate post shown at the extreme right of Figure 1, the dotted line showing in Figure 12 indicating an intermediate position of the gate, as it is being lowered into or raised from its operative 60 position.

Figure 13 is a cross sectional view on an enlarged scale taken on line 13—13 of Figure 12 with the gate lowered and the gate guide shown in engagement with the gate post guideway.

65 Figure 14 is a perspective view on an enlarged scale of one of the floor plates shown in Figures 1 and 2.

Referring now to the drawings, and particularly Figures 1 and 2, these illustrate the invention as embodied in a railway refrigerator car. The construction for both ends of the car, according to this invention, is substantially the same, so that description and illustration of only one end of the car are necessary to a complete 75 understanding of the invention.

The car 1 has the usual loading space 2, ice chamber 3 (at each end), and floor 4. Floor stringers 5, and slats 6 provide a floor deck 7, which may be removable or permanently secured in place.

The floor 8 of the ice chamber 3 is at a lower 5 level than the car floor 4, so that any water collecting on the latter may drain into the ice chamber. This water may result from the so-called practice of "top icing" or "package icing" 10 for the intensive refrigeration of such commodities as lettuce, celery, et cetera, in order to preserve crispness.

When the car is used to transport shipments in sturdy containers, the car floor deck 7 is 15 used as the supporting deck, and the containers may be piled from the floor deck to the car ceiling 9. Where, however, the shipment is in bulk, bag, sack or other flexible containers, and of such nature that it may be damaged by single 20 deck loading, a second or upper deck 10 is provided to divide the load. For this purpose the car is provided with a folding upper deck 10, formed of two sections 11 and 12, secured to the opposite side-walls of the car; and each section 25 comprises one or more folding deck racks 13. In the drawings each section 11, 12 consists of four deck racks 13, although any suitable number of racks in each section may be provided. This arrangement is understood to be duplicated in that 30 part of the car that is not shown in Figure 1.

The car side-walls are provided with upper and lower facings 15, 16, the upper one 15 being set back so that the two facings are in different vertical planes. The off-set distance between 35 the planes of the exposed surfaces of the two facings 15, 16 is approximately the same as the depth of thickness of an individual upper deck rack 13. Thus, when a deck rack, in raised position, lies along the upper facing 15, as shown 40 at the left side of the car in Figure 2, it completely fills the side-wall recess so that the exposed bottom or side 17 of the deck rack, and the exposed surface of the lower facing 16 are in substantially the same vertical plane. This 45 construction provides loading space side-wall surfaces in substantially one plane when only a single deck is used, and an upper deck section is stored along a car side-wall. The invention, therefore makes it possible to convert the storage space of a car, truck or other vehicle from a double deck storage space, to a single deck loading space of standard inside dimensions. The outside dimension for the width of the car 50 may be increased by twice the thickness of a 55 deck rack, so that, in the case of refrigerator cars, the required amount of insulation may be provided between upper facing 15 and the outer sheathing 20 of the car. In other words each outer sheathing 20 is moved outwardly, the 60 distance that the upper facing 15 is set back from the lower facing 16.

An angle-iron rail 22, having a horizontal flange 21 extends longitudinally of the car along the sides at the upper edge 24 of the lower facing 16, and serves as a hinge support for one side 25 of the deck racks 13. The rail 22 may be of other than angle iron section, but it is preferably of such section as affords a horizontal flange, with another angularly disposed flange 70 to facilitate its fastening to the framing of the car or vehicle. The vertical leg 26 of the angle-iron rail extends downwardly and to the rear of the lower facing 16 (see Figure 2). Bolts 27, with nuts 28, secure the vertical leg 26, at the 75

lower edge 29 of the facing 15, to the car framing 19, as shown in Figure 2. The upper edge 24 of the lower facing 16 overlies the vertical leg 26 of the angle-iron 22. The horizontal flange 21 of the angle-iron 22 is provided with spaced holes 31 to receive the shanks 32 of rack pintle pedestals 33, each of which supports a pintle 34 (see Figure 10). The holes 31 are somewhat larger than the shanks 32, so that the latter may be adjusted to the desired position. Nuts 35 threaded on the shanks 32 hold the latter in place. The ends 36 of the shanks may be riveted over the nuts 35 to permanently secure the assembly.

As the deck racks 13 and their supports and fastenings are alike, it is only necessary for an understanding of this invention, to describe one deck rack and its supports and fastenings.

Each deck rack 13 comprises a rectangular frame 31, consisting preferably of sheet metal members 38, 39, 40, 41, each having at one side, an inturned flange 42. A middle cross member 43, serving as a brace, extends between and is secured to opposite sides 39, 40 of the frame 31. The frame members and the cross member may be welded together, or joined in any suitable manner. The cross member 43 in cross section is doubled upon itself to form a centrally disposed upstanding flange 44. This member is also provided with flanges 45, 46 extending from either side of the upstanding flange 44. Two sets 47 and 48, of wooden or metal slats 49 are provided for each rack 13. The slats 49 of each set are spaced apart in parallel arrangement and extend between the flange 42 at one end of the rack frame 31 and one of the flanges 45, 46 of the cross member 43. The ends 50 of the slats 49 may be secured to the flanges 42, 45, 46 by any suitable means, for example, by screws or rivets 51. The outer sides 52 of the outermost slats in each set rest on the flanges 42 of the frame members 39, 40. Figures 2, 8, and 10 show the flanges 42, 45, and 46 fitted into the slats 49, so that the flanges and slats together present a substantially flush surface on both sides. If desired other suitable material may be substituted for the slats 49.

The side members 39, 40, and also the end member 41 of the rack frame 31 are preferably of U-shape in cross section, (see Figures 7, 8, and 9) to provide a continuous channel or recess 53 extending around three sides of the rack. The aforementioned flanges 42 extend inwardly from one edge 54 of the frame members 39, 40, 41. The other end of the rack frame comprises a metallic member shaped to form a hollow tubular frame element 38, with an inturned flange 42 (see Figure 10). The open ends of member 38 are provided with spools 55 having sockets 56 which latter serve as pintle or hinge pin bearings. The spools 55 are preferably welded in position in the ends of the member 38. When a deck rack 13 is mounted on the angle-iron rail 22, the sockets 56 of its two spools 55 receive a pair of pintles 34, so that the deck rack is hinged for swinging movement from a load-supporting horizontal position to the folded or vertical position as shown by the two positions of the deck racks in Figures 1 and 2.

To support the free outer end of each rack 13 in its load-supporting position, there is provided a U-shaped member 51 comprising a pair of legs 58 (which may be formed of pipe sections) and a connecting element or rod 59 with bent ends 60, extending into the open ends of the legs 58, to

which the ends 60 may be rigidly secured as by welding. Clips 61, which may be welded to the end member 41 of the rack frame 13, secure the connecting branch or rod 59 to the rack so that the supporting member 51, as a whole, has pivotal movement from the position where it supports the free outer end of the rack (see lowered racks in Figure 1) to a position where it lies completely within the continuous channel in the rack frame provided for that purpose (see Figures 7 and 9).

Each rack side frame member 39, 40 is provided with a spring clip 62 suitably fastened in the channel 53 to releasably secure the adjacent leg 58 in inoperative position within the channel 53. Figure 9 shows, in full lines, a leg 58 held by a clip 62, and in dotted lines, the leg 58 freed of the clip and swung outwardly by a spring 63 provided for that purpose.

Plates 64 (see Figure 14) having upstanding projections 65 are suitably secured in the car floor 4, and these plates are so positioned that each of the upstanding projections 65 will engage a leg of four racks 13 having their adjacent corners meeting vertically above the plate 64. The projections 65 are shaped to enter open ends of the supporting legs 58 when the latter are lowered to the rack supporting position. The rack legs 58 extend through or between the closely arranged floor rack slats 6, which latter serve to brace the legs. Where the legs extend through the floor slats 6, the latter are provided with suitable apertures 66 which may be reinforced by perforated metallic plates 67, as shown in Figures 1 and 2. Means are, therefore, provided not only to brace the legs between their ends, but also to prevent their shifting out of a proper rack supporting position.

A ceiling corner strip 68 of approximately the same thickness as a deck rack 13 is secured to the car wall at the upper edge of each of the facings 15, and latching devices 72 are secured to the strip 68 at positions therealong such that a latch is provided for retaining each individual rack in its upright, or out-of-the-way position, against the side wall of the car. A securing plate 69, (see Figure 5) to be secured to the strip 68, and provided with a projecting shank 70, the latter being square or rectangular in cross section, is employed as a support for each of the latches 72. A key-hole slot is provided in the latch, such that the latch may not turn except when the shank 70 lies within the enlarged opening 74 of the slot. With this construction of latch and shank, the latches will be effective to retain the racks in their vertical position, as shown at the left in Figure 2; and will require positive operation to release the racks when these are to be moved into their operative, load-supporting horizontal position. As the latches are operated to release the racks, they may be rotated and moved to take the horizontal position, as shown at the right in Figure 2, in which position they will be secured and retained by virtue of the square or rectangular shank 70 which prevents turning and resists endwise movement of the latch. The outer end of the shank 70 is enlarged or provided with retaining shoulders to prevent displacement therefrom of the latch element 72.

It will now be clear that when a deck rack 13 is in use, the supporting legs 58 extend to the car floor, engage projections 65, and are braced by slats 6 and/or plates 67. When the deck rack is to be moved to an out-of-the-way position, 75

it is swung or folded on its hinge connections until it lies within the set-back part or recess of the side-wall, and against the upper facing 15. Catch 72 is now shifted longitudinally until shank 70 is in the enlarged portion 74 of slot 71, and then swung to a vertical position and moved downwardly by grasping handle portion 75; or the catch may drop due to the force of gravity, so that the lower end of the catch overlies a portion of the upper edge of the deck rack (as shown in Figure 2). The deck rack 13 will then be secured against movement, and the supporting legs 58 can be swung past clips 62 to a position within the channel 53 of the rack frames 37.

15 The clips 62 retain the legs 58 in this position.

When all of the racks have been raised, the car may be used for single deck loading, and the loading space side-wall surface, formed by strip 68, deck racks 13, and a facing 16, will present 20 a substantially unbroken, smooth, flush surface appropriate for some types of loading. It will thus be seen that the set-back construction of the side wall defines a recess area for receiving the folded deck sections, so as to afford a substantially flush side wall surface when the racks 25 are in their folded position.

To release a rack 13 from its catch 72, the latter must first be raised toward the car ceiling until shank 70 enters enlarged opening 74. The catch is then turned through an angle of approximately 90° and shifted so that shank 70 enters the elongated portion 73 of slot 71 to hold the catch in the horizontal position. The catch is preferably rounded at its upper end 76 so that it will not engage nor bind on the car ceiling 9 during its turning movement. When the upper deck racks 13 are in their load supporting position, the upper loading space, between side walls is somewhat wider than the lower loading 40 space, as the side wall facings are in different planes.

To provide end supports for the load on the upper rack sections 11, 12 at the deck edge 17, adjacent the center of the car, a gate 78 is provided for each of the upper decks at the car door opening. Each gate 78 comprises slats 79 (see Figure 11), and spaced transverse brace strips 80, 81 intermediate the ends. A pair of plates 82, 83 at each end of the gate embrace 45 and are bolted or riveted to the ends of slats 79. The outer edges of the plates 82, 83 project beyond the edge of the gate and are formed into a T-shaped guide 84, as clearly shown in Figure 13. Gate posts or gate frame members 85, 50 at either side of the car door openings and on both sides of the car, have vertical grooves 86, 55 with facing plates 87, 88 secured thereto which extend over the edge of the groove 86 to provide a T-shaped guideway 89 (see Figure 13) for the gate guides 84. In lieu of the latter guides, rollers (not shown) may be used, such 60 rollers being mounted upon the gate and operating within the T-shaped guideway 89. The facing plate 87 extends only part way up the 65 post, and above this plate, one side of the groove is removed at 121 (see Figures 1 and 12), so that the gate may swing clear of the post 85 when the gate 78 is raised and hooks 90 enter the apertures 91 in gate straps 80.

70 A plate 92, bolted to the car ceiling 9, pivotally supports the T-shaped ends 93 of hooks 90 which extend through a slot (not shown) in the plates 92. These plates and hooks may be assembled by first passing the hook through the slot and then fastening the plate 92 to the car ceiling.

Two hooks 90 are provided for each gate 78, and each hook engages in an opening 91 in one of the brace straps 80. The hooks are positioned over the edge of the decking and in substantially the vertical plane of the gate posts 85. The gate 78, when suspended from the hooks 90 in a vertical position (see dotted line position in Figure 12) may be readily swung to its horizontal out-of-the-way position (full line position in Figure 12) beneath the car ceiling. In the latter position, the free end of the gate is supported by a catch 95 which may be pivotally moved so that its end 96 underlies a part of the gate and engages the bent section 97 of gate strap 80. The catch 95 has an apertured flat end 98 15 pivotally secured to a support 99 bolted to the car ceiling.

Brace straps 80, 81, of the gates are bent at their lower ends 97 to form outwardly projecting portions 100 and then a downwardly projecting edge 101. With a gate 78 in the horizontal position, as shown in Figures 1 and 12, at the end of a deck section, to lower it into operative position, the catch 95 is rotated to release one end of the gate which may then be swung on hooks 90 to a vertical position (as shown in dotted lines in Figure 12). In so swinging, the gate moves into a position between the gate posts 85 at opposite sides of the car and above the facing plate 87. The upper part of facing plate 88 and the gate post 85 provide a groove (a continuation of the right side of the guideway 89 in Figure 13) for aligning the gate guides 84 with the lower gate post guideways 89. Upon release from the hooks 90, the gate 78 will drop so that its T-shaped guides 84 will enter the guideways 89 at each side of the car. When the gate 78 takes its operative position (see lowered gate in Figure 1), the brace strap edges 101 fit over the adjacent rack frame side members 39, 40 of the two end 40 deck racks and project down in back of the same as shown in dotted lines in Figure 8 to brace the gate and prevent its bulging due to end pressures of the load. Part of the upper deck load will rest on the horizontal portions 100 of the brace straps, 45 and thereby serve to hold the gate 78 in proper position and against accidental release therefrom.

Ice in chamber 3, indicated at 102, is supported by an ice rack 103 resting on transverse beams 50 104. In order to provide for circulation of the air around the ice, screens 105 are spaced from the walls of the ice chamber to provide vertical air channels 106. The bulkhead 107, separating the ice chamber 3 and loading space 2, is provided with top and bottom openings 108, 109 to 55 permit air circulation between the two chambers. To provide for additional air circulation for the car, when it is converted for double deck loading, each bulkhead 107, at opposite ends of the 60 car may be provided with an opening 110 adjacent, and preferably just below, the level of the upper deck when in use. Air therefore, may pass between the ice chamber 3 and the space immediately below the upper deck. Air may also circulate between the superposed loads on the two 65 decks. The spaces 111 between the slats of the upper deck, and similar spaces 112 between slats of the floor racks provide for circulation of air through the load.

When the car is used for single deck loading, circulation through the auxiliary opening 110 may be undesirable or unnecessary. It may also be desired under some circumstances to shut off circulation through these openings when both 75

decks are provided for the load. A sliding closure 113, and frame 114 are, therefore, provided at the opening 110 and within a recess in the bulkhead, so as not to project into the loading space 2. The frame has an opening 115 in alignment with the bulkhead opening 110. At its sides the frame 114 is formed to provide a pair of channel-shaped guideways 116. The closure 113 is stamped from sheet metal (though it may also be suitably formed of other material) and has side flanges 117 which slide in the frame guideways 116. A flange 118 at the bottom of the closure 113 fits within a channel groove at the base of the frame when the closure 113 is lowered to close the opening 110. An outwardly projecting flange 120 at top of the closure 113 is provided, which serves as a handle for moving the closure. The closure may be provided with any suitable means for holding it in raised, lowered, or intermediate positions.

It will be understood that while the invention is particularly applicable to railroad refrigerator cars, it offers obvious advantages when practiced in connection with other types of railway and road vehicles including so-called ventilator cars, box cars, express cars, and motor trucks, as well as with ships and in storage warehouses.

Only one embodiment of each of the features of this invention have been shown and described, but other forms and modifications embodying the invention may be readily devised within the spirit and scope of the invention, as defined in the following claims.

1. In a railway car construction, a side wall therefor presenting to the interior of the car upper and lower faces, the upper face being set back from the vertical plane of the lower face, a flanged rail providing a ledge along the upper edge of said lower face, the vertical flange of said rail being secured to said wall and extending downwardly at the rear of said lower face, folding deck racks pivotally secured to said ledge for movement from a horizontal load-supporting position normal to said wall to a folded position along and parallel to the upper of said side-wall faces, and means which cooperates with said ledge to support said racks in the horizontal load-supporting position.

2. In double deck equipment for railway cars and other vehicles, the combination of a folding deck rack extending along an inner side-wall, the said rack having pintle-receiving sockets at one side thereof, a support for said side of the deck rack, said support comprising a rail having a vertical flange secured to said inner side-wall and a horizontal flange projecting outwardly from said vertical flange, and pintles mounted on said horizontal flange and spaced therealong to provide a hinge support for the said folding deck rack.

3. In a railway car having provision for double deck loading the combination comprising, folding rack sections adapted to form a second load supporting deck within the car, inner car side-walls having a set-back portion to receive the rack sections in their folded inoperative position, and means for supporting said rack sections in deck forming position and providing for swinging movement of said sections to folded position within the set-back portion of said side-walls, said means including a flanged rail adjacent the bottom edge of said set-back portion and providing a horizontally disposed ledge, and pintles secured to the rail for hinge connection to the

racks to support the latter for said swinging movement.

4. In a railway car having provision for double deck loading the combination comprising, a folding deck rack hinged at one end to an inner car side-wall for swinging movement and having an open channel extending along three sides thereof, a substantially U-shaped member for supporting the free end of said rack and comprising a pair of legs and a connecting branch, and means for hinging the connecting branch to said rack so that said member may be swung to a position wholly within said channel.

5. In a railway car having provision for double deck loading the combination comprising, a folding deck rack hinged at one end to an inner car side-wall for swinging movement, a supporting leg member hinged to said deck rack, means for releasably securing said leg in folded position against said deck rack, and means including a resilient member for projecting the free end of said leg member away from said rack upon release of said securing means.

6. In a railway car having provision for double deck loading the combination comprising, a folding deck rack hinged at one end to an inner car side-wall for swinging movement, a depending leg member secured to said deck rack having an opening in its outer end, and an upstanding lug fixed to the car floor in position to be received by said opening when the leg is in a vertical rack supporting position.

7. In a railway car having provision for double deck loading the combination comprising, an upper deck rack extending along and supported at one side from an inner car side-wall, a floor rack, and supporting legs for said upper deck rack extending through said floor rack to the car floor, said floor rack having means for engaging said legs to brace them intermediate their ends.

8. In a railway car having provision for double deck loading, an upper folding deck rack mounted on hinge pintles secured to an inner car side-wall and comprising a frame member formed with hollow ends and having a flange extending along one side thereof, pintle-receiving spools in said hollow ends, and load-supporting slats secured to the flange of said member.

9. A refrigerator car or vehicle comprising a refrigerant chamber, a loading space, an intermediate bulkhead, an upper folding deck adjacent said bulkhead and within said loading space, said bulkhead having an air circulating passageway therethrough opening into said loading space at a level somewhat below that of the load supporting position of said upper deck, and means for controlling air circulation through said passageway.

10. In a refrigerator car or vehicle, a bulkhead separating a refrigerant chamber from the loading space of the car, ventilation passages providing for air circulation at the top and bottom of the bulkhead, an auxiliary ventilation passage through the bulkhead intermediate the said top and bottom passages, a frame in said bulkhead aligned with said auxiliary passage, and a plate slidably in said frame constituting an adjustable closure for regulating circulation of air through said auxiliary passage.

11. In a railway refrigerator car, a bulkhead separating a refrigerant chamber from the loading space of the car, ventilation passages providing for air circulation at the top and bottom of the bulkhead, an auxiliary ventilation passage

- through the bulkhead intermediate the said top and bottom passages, a frame in said bulkhead aligned with said auxiliary passage, the said frame having side members comprising vertically disposed channel guide elements, a plate slidable in said guide elements to constitute an adjustable means for regulating air circulation through said auxiliary passage, and means for retaining the plate in an adjusted position.
12. In a railway car construction, a load supporting deck within the car, a gate for said deck, means for maintaining said gate in vertical operative position transverse of said deck, and means for suspending said gate from the car ceiling in a horizontal inoperative position, said suspending means including a connection in substantially the vertical plane of said gate when in said operative position.
13. In a railway car construction, a load supporting deck within the car, a sliding gate for preventing shifting of the load on said deck, means for vertically guiding said gate to a position transverse of said deck, means for releasably supporting said gate in horizontal position closely adjacent and beneath the car ceiling, said supporting means including releasable hinge connections in substantially the vertical plane of said vertical guide, and means to align the gate with said vertical guide when said gate is swung on said hinge connections.
14. In a railway car construction having provision for double deck loading with folding rack sections adapted to form a second load supporting deck within the car, a gate for said deck, means for guiding said gate for vertical movement to a position transverse of said deck in its load supporting position, and means for holding said gate in a horizontal inoperative position including releasable hinge connections upon which said gate may swing from its horizontal position to a position for engagement with said guiding means.
15. In a railway car construction having provision for double deck loading with folding rack sections adapted to form a second load supporting deck within the car, a gate for preventing shifting of the load on said deck, the said gate in operative position extending transversely of the car adjacent the door opening, quickly releasable hinge connections on the car ceiling for supporting one side of said gate, and means for detachably securing said gate in horizontal position when swung to such position on said hinge connection.
16. In a railway car construction, folding load supporting racks adapted to form a second load supporting deck within the car, an end gate for said deck, and means for suspending the gate from the ceiling of the car comprising a strap secured to said gate and having an opening therein, a slotted plate secured to the car ceiling, and a hook supported by and extending through said slotted plate for engagement with said strap opening.
17. In a railway car construction, folding load supporting racks adapted to form a second load supporting deck within the car, a gate post within the car and positioned beside a door opening and having a guideway substantially T-shape in cross section, a gate for preventing shifting of the load on said deck, and a pair of plates secured to the end of said gate with adjacent free edges projecting therefrom to form a guide substantially T-shape in cross section for sliding engagement in said guideway.
18. In a railway or other vehicle construction, folding load supporting racks adapted to form an auxiliary load supporting deck within the vehicle, a gate for said deck and having guides at its ends, gate posts within the vehicle, the said posts having longitudinal grooves for receiving said guides, and plates secured to said posts beside said groove with their edges overlying a part of said groove for engagement with the guides of said gate to retain said guides in the groove.
19. In a railway car construction, folding load supporting racks adapted to form a second load supporting deck within the car, a gate for said deck and having flanged guides at its ends, gate posts within the car and having longitudinally extending grooves for receiving said guides, and plates secured to said posts beside said groove and having an edge extending over part of said groove for engagement with the said guide flange of the gate to retain said guide in said groove.
20. In a railway car construction, folding load supporting racks adapted to form a second load supporting deck within the car, a gate post at the side of said deck and having a guideway, and a gate for said deck comprising a plurality of slats, and a pair of plates secured to opposite faces of the ends of said slats, said plates projecting from said slats and formed into a guide for sliding engagement in said guideway.
21. In a railway car construction, folding load supporting racks adapted to form a second load supporting deck within the car, a gate for said deck, means at opposite sides of the car for supporting said gate in position transverse of said car to prevent shifting of the load on said deck, and means for attaching said gate intermediate its ends to said deck to maintain it in cooperating relation to the deck and to brace the gate against bulging under load.
22. In a railway car construction, folding load supporting racks adapted to form a second load supporting deck within the car, a gate for said deck, means for supporting said gate in position transverse of said car to prevent shifting of the load on said deck, and means for attaching said gate intermediate its ends to said deck to maintain it in cooperating relation to the deck and to brace the gate against bulging under load, said means comprising a member projecting outwardly from the gate to lie on the top surface of said deck and downwardly to lie behind a part of said deck.
23. In a railway car having provision for double deck loading and convertible to provide an unobstructed loading space for single deck loading, the combination comprising inner car side-walls having set back portions for receiving stored deck racks, an auxiliary deck extending substantially from car side-wall to car side-wall and formed of deck racks foldable into said set back portions to provide together with said inner car side walls substantially flush loading space wall surfaces, a floor deck, and legs to extend vertically between said decks for supporting said foldable racks in their operative load supporting position, said legs being foldable in association with one of said decks to an out-of-the-way position adjacent and beyond the surfaces defining the loading space when converted for single deck loading, whereby provision is made for storage of the auxiliary deck and its supports to leave the loading space substantially free and unobstructed for single deck loading.
24. In a railway car having provision for double deck loading and convertible to provide an un-

obstructed loading space for single deck loading, the combination comprising inner car side-walls having set back portions for receiving stored deck racks, an auxiliary deck formed of deck racks 5 foldable into said set back portions to provide together with said side-walls substantially flush loading space wall surfaces, a floor deck, and legs to extend vertically between said decks for supporting said foldable racks in their operative 10 load supporting position, said legs being foldable to an out-of-the-way position in interfitting association with one of said decks whereby the auxiliary deck and its support may be stored to leave the loading space unobstructed for single deck 15 loading.

25. In a railway car having provision for double deck loading the combination comprising, a folding rack adapted to form at least part of a second load supporting deck within the car, an inner car side-wall along which the rack is arranged in its deck forming position, and means including foldable supporting legs for supporting said rack in such position, the said wall being recessed to receive the rack in its folded inoperative position, 20 and the said rack being recessed to receive said legs in their folded inoperative position.

26. In a railway car having provision for double deck loading the combination comprising, a folding rack adapted to form at least part of a second load supporting deck within the car, an inner car side-wall along which the rack is arranged in its deck forming position, and means including foldable legs for supporting said rack in such position, the said wall being recessed to receive the rack in its folded inoperative position and presenting a substantially flush loading space side-wall surface with the racks in said folded position, and the said rack being recessed to receive said legs in their folded inoperative position. 35

40. 27. In a railway car having provision for double deck loading, the combination comprising folding racks extending along opposite recessed inner car side-walls and adapted to form a second load supporting deck within the car with the meeting edges of opposite racks adjacent the longitudinal center of the deck, and means for individually supporting said racks in deck forming position, each of said means including a substantially 45 U-shaped rack support comprising a pair of legs and a connecting branch extending along substantially the whole length of a rack at its edge adjacent said deck center, each of said racks in its load-supporting position being adapted to rest 50 on one of said connecting branches and be supported by its legs, said racks and legs being foldable to an inoperative position within the recesses of said side-wall.

28. In a railway car or other vehicle construction, a deck rack, a side-wall along which said

5 rack is arranged and presenting to the interior of the car upper and lower faces, the upper face being set back from the vertical plane of the lower face, a rail providing a horizontal ledge along the upper face of said lower face and extending between the two faces, and pintles mounted on said ledge and spaced therealong to provide a hinge support for said folding deck rack.

29. In a railway car having provision for double deck loading, an upper deck rack mounted along an inner car side-wall and comprising a metallic frame of channel shape in cross section on at least three sides of the rack to provide recesses for receiving rack supporting members, said frame also having inwardly projecting slat supporting flanges, a cross brace member positioned intermediate the ends of said frame and secured to opposite sides thereof, said brace member being T-shaped in cross section to provide slat supporting flanges extending from opposite sides thereof and in the plane of the rack, and two series of spaced slats arranged on opposite sides of said brace member and secured to the slat supporting flanges of said frame and brace member. 10 15 20 25

30. In a railway car having provision for double deck loading, an upper deck rack mounted along an inner car side-wall and comprising a metallic frame of such shape in cross section on at least three sides of the rack as to provide recesses for receiving rack supporting members, said frame also having inwardly projecting slat supporting flanges, a cross brace member positioned intermediate the ends of said frame and secured to opposite sides thereof, said brace member having 30 35 40 slat supporting flanges extending from opposite sides thereof and in the plane of the rack, and two series of spaced slats arranged on opposite sides of said brace member and secured to the slat supporting flanges of said frame and brace member. 45

31. In a railway car having provision for double deck loading, a plurality of deck racks arranged along an inner car side wall for folding movement from a horizontal deck forming position to a vertical inoperative position, each deck rack comprising a frame and a plurality of slats secured therein, and each frame having the opposite ends of one side provided with sockets, and means for supporting said frame sides to provide for swinging movement of said deck racks, said means including a pintle between each two adjacent deck racks and having its opposite ends in engagement with the adjacent sockets of said two deck racks, a member supporting each pintle intermediate its opposite ends, and a flanged rail secured to the inner car side-wall and carrying said supporting member. 50 55 60

EDWARD A. SWEELY.
NORMAN T. ANDERSON.

CERTIFICATE OF CORRECTION.

Patent No. 2,077,649.

April 20, 1937.

EDWARD A. SWEELEY, ET AL.

It is hereby certified that error appears in the printed specification of the above numbered patent requiring correction as follows: Page 7, second column, line 5, claim 28, for the word "face" first occurrence read edge; and that the said Letters Patent should be read with this correction therein that the same may conform to the record of the case in the Patent Office.

Signed and sealed this 1st day of June, A. D. 1937.

(Seal)

Henry Van Arsdale
Acting Commissioner of Patents.
